DISTILLING APPARATUS

Matthew W. Svetlick and Walter F. Svetlick,
Pittsburgh, Pa.

Application October 9, 1941, Serial No. 414,320

1 Claim. (Cl. 202—186)

This invention relates to a distilling apparatus, and contemplates among its important objects and advantages to provide an apparatus of the character described, which is efficiently operable to distill any distillable liquid, which will fractionate and separately collect the distillate in accordance with the degree of the latter's resistance to total vaporization and its susceptibility to condensation, which functions automatically during the distilling operation, which is simple in its construction and arrangement, positive in its action, and comparatively economical in its manufacture, installation, operation and maintenance.

With the foregoing and other objects in view which will appear as the description proceeds, the invention resides in the novel construction, combination and arrangement of parts herein specifically described and illustrated in the accompanying drawing, but it is to be understood that the latter is merely illustrative of an embodiment of the invention, and that the actual needs of practice and manufacture may require certain mechanical variations from the embodiment shown. It is, therefore, not intended to limit the invention to the disclosure thereof herein illustrated, but rather to define such limitations in the scope of the claims hereunto appended.

In the drawing, the figure is a front elevational view of a distilling apparatus constructed in accordance with and embodying the present invention.

Referring in detail to the drawing 1 denotes a boiler or still, and 2 represents a condenser. The latter and said boiler or still may be of any suitable construction for the purpose employed. The still includes a removable head 4, which is connected with one end of a conduit or pipe 3. The latter is disposed horizontally and employed for conveying the distillates from the still to a condenser 2, or to any other type of receiver required, and may be insulated with any suitable material to prevent or minimize loss of heat therefrom.

The condenser 2 includes a condenser coil 5, which is connected with the pipe 3 by means of a drop pipe 28 and a fitting 29. The latter is provided with a control valve 30 and connects with an extension pipe 36 also provided with a control valve 31. By the regulation of the valves 30 and 31 the distillates may be selectively directed either into the condenser through the pipe 28, or to any other provided receiver through the pipe 36.

5 The still 1 is provided with all necessary appurtenances, including a content gauge 6, a pressure gauge 1, a drain valve 25, an automatically operable pressure relief valve 26, and an inlet fitting 27. The condenser 2 is provided with a drain cock 8, an inlet fitting 32, and an overflow fitting 37.

10 A pair of receptacles, respectively indicated at 9 and 10, is suspended from the pipe 3. The receptacle 9 is carried and communicably joined with the pipe 3 by a fitting 13 having a control valve 33, and by a sinuous suspension tube 14. The receptacle 9 is disposed adjacent to the still 1, and the receptacle 10 is spaced from the former. The receptacle 10 is likewise carried and communicably joined with the pipe 3 by a fitting 15 including a control valve 34, and by a straight or preferably a sinuous suspension tube 16, as shown.

15 The condenser 2 carries a receptacle 11, which is communicably connected with the top convolution of the condenser coil 5 by means of a suspension tube 24, which latter is provided with a control valve 35. The receptacles 9, 10 and 11 are preferably constructed of glass to visibly display their contents, but obviously may be constructed of any other suitable material. Each of the receptacles is provided with a drain valve 12 operable for removing the contents therefrom when required. While the disclosed embodiment 20 of the invention shows but two receptacles 9 and 10 suspended from the pipe 3, it is to be noted and understood that the number of such receptacles and the spaced relations of the latter may be varied and employed to best meet any required 25 condition found in practice, without departing from the spirit or sacrificing any advantages of the invention.

20 It is, of course, apparent that the receptacles 9, 10 and 11, may be supported in any other suitable manner, but it is essential to the successful 30 operation of the device that the receptacles with their suspension elements allow gravity flow of any matter to be deposited therein during the 35 distilling operations.

40 A tubular glass cylinder 17 is connected in the pipe 3 adjacent to the condenser 2, and a similar tubular glass cylinder 18 is carried at the lower end of the condenser and is connected with the lower or outlet end of the condenser coil 5. The 45 glass cylinders 17 and 18 are susceptible to the penetration of ultra-violet rays, and an ultra-violet ray lamp 19, carried by an adjustable fixture 20 mounted on the pipe 3, is associated with 50 the cylinder 17. In like manner, an ultra-violet

ray lamp 21, carried by an adjustable fixture 22 mounted on the condenser 2, is associated with the cylinder 18. The latter is provided with a discharge valve 23 operable for permitting and controlling the flow of condensed distillate from the coil 5. It is evident that any other suitable types of ultra-violet ray producing appliances may be employed instead of the lamps 19 and 21 as embodied in the present disclosure.

The operation of the improved distilling apparatus is as follows: The liquid to be distilled is placed within the still 1 and heated to create and produce continuous vaporization of the said liquid. Such vaporization or distillate in vapor form will rise in the still to enter and pass into the pipe 3. All distillates retaining their full vapor form will pass through the entire length of the pipe 3 into the condenser 2 or into any other provided receiver. However, all of the distillate will not retain its pure or full vapor form, as the process of condensation will begin as soon as the vaporized distillate passes into the pipe 3 from the still, and such condensation will increase in proportion to the increasing distance of travel of the distillate within the pipe 3 from the still.

As the condensed distillates form within the conveying pipe 3, it will be removed or drained from the latter in the sequence of its formation, and collected in the various receptacles 9 and 10 provided for that purpose. If the control valve 35 is open condensed distillates will also be removed from the top of the condenser coil 5.

If the distilling apparatus is employed for distilling alcoholic spirits from fermented liquors, all fusel oil and deleterious acids are completely removed from the distillate. In like manner, if the device be employed in the distillation of oils or any other distillable liquids, the entire variety of readily condensable distillates forming within the conveying pipe 3, is removed and collected in the various spaced receptacles in the sequence in which the latter are positioned in their connection with the pipe 3. Such collected distillates may be valuable, worthless, or of any nature or character whatsoever, but any distillates so forming in the pipe 3 are removed in the operation of the improved apparatus.

The use of the sinuous suspension tubes 14 and 16 retards the gravity flow of the liquid matter

from the pipe 3 into the receptacles 9 and 10, whereby such matter is cooled to some extent and is not liable to fracture the glass receptacles receiving same. The tubes 14 and 16 may be constructed of copper, heat-resisting glass, or of any other suitable material.

During the passage of the distillates through the glass cylinder 17, prior to condensation, and during the passage of the condensed distillates 10 through the cylinder 18 subsequent to condensation, the product will be twice subjected to treatment by ultra-violet rays from the operation of the lamps 19 and 21. Such treatment may be employed to add valuable and essential vitamin 15 constituents to the product if the latter is of the character to be used for human consumption.

From the foregoing description taken in connection with the accompanying drawing, the construction and the method of operation of the 20 invention will be readily apparent to those skilled in the art to which the invention appertains. Extensive experiments have conclusively proven that a distilling apparatus constructed and operated in accordance with the present disclosure, 25 will function economically and efficiently for the purposes and in the manner set forth.

What we claim is:

In a distilling apparatus of the character described, the combination of a still, a condenser 30 including a coil, a horizontally disposed pipe connected with said still and with said condenser, a tubular glass cylinder connected in said pipe adjacent to said condenser, a tubular glass cylinder connected to the lower end of said coil, a 35 plurality of sinuous tubes connected with and depending from said pipe in spaced relation to each other, a receptacle carried by each of said tubes for separating and collecting by gravity action liquefied matter from the distillate during 40 the passage of the latter through said pipe, a receptacle connected adjacent to the upper end of said coil for draining liquefied matter from the top of said coil, and a pair of lamps adjustably supported by the apparatus and acting on 45 respective said cylinders operable for treating the distillate to ultra-violet rays prior and subsequent to condensation.

MATTHEW W. SVETLICK.
